UNITED STATES PATENT OFFICE.

ERNEST LORIN FULLER, OF MALDEN, MASSACHUSETTS, ASSIGNOR TO TECHNICAL SUPPLY COMPANY, OF SCRANTON, PENNSYLVANIA, A CORPORATION OF NEW JERSEY.

DRAFTING APPARATUS.

1,314,323.

Specification of Letters Patent. Patented Aug. 26, 1919.

Application filed October 13, 1917. Serial No. 196,456.

To all whom it may concern:

Be it known that I, ERNEST L. FULLER, a citizen of the United States, residing at Malden, in the county of Middlesex and 5 State of Massachusetts, have invented certain new and useful Improvements in Drafting Apparatus, of which the following is a specification.

My invention relates to improvements in 10 drafting apparatus.

One of the objects of my invention is to provide a drafting apparatus comprising a straight-edge provided with a parallel motion attachment attached to the straight- 15 edge and to a drawing-board, table, or any flat surface which will permit the straight-edge to be freely moved and to be maintained constantly in an absolutely parallel position with respect to the angle at which it 20 is placed, when moved over the surface of the drawing-board.

Another object is to provide an attachment for a straight-edge, which will allow the straight-edge to be readily and quickly 25 adjusted to any angle desired or its angle changed without re-adjustment or change of position of the moving parts or the cords.

Another object is to provide means for locking and holding a straight-edge at a 30 fixed angle, after it has been placed at the particular angle desired, so that while the angle of the straight-edge cannot be changed without unlocking it, the straight-edge, nevertheless, may be simultaneously moved 35 over the surface of the drawing-board and the same angle will be constantly and accurately maintained while it is locked at that angle.

Another object is to provide a parallel 40 motion attachment which may be readily attached to any straight-edge, drawing-board or any flat surface.

Another object is to provide a parallel motion attachment in which all the wheels 45 are incased, so that the attachment cannot become unstrung, notwithstanding how quickly the straight-edge is moved or its position changed.

Another object is to provide a parallel 50 motion attachment which will allow full play to the straight-edge for continuous drawing, either horizontally or vertically, clear across the drawing-board.

In attachments for allowing parallel motion of a straight-edge in general use there

is no means for permitting the angle of the straight-edge to be changed to any great extent without either practically taking the attachment apart and completely readjusting the cords and their coöperating parts, 60 or releasing some operative part, while in my device none of the moving parts or the cords have to be readjusted, except a thumb-nut and the coöperating parts, in order to change the angle. 65

In the accompanying drawings, Figure 1 is a plan of a drawing-board and my improved drawing apparatus, comprising the straight-edge and parallel motion attachment for the same. Fig. 2 is a diagrammatic view showing the course of the cords. Fig. 3 is a plan of one of the end casings. Fig. 4 is a front elevation of one of the end casings. Fig. 5 is a plan of the center casing showing the cords in dotted outline. 70 Fig. 6 is a central longitudinal section of the center casing on the line $x-x$, Fig. 5. Fig. 7 is a vertical cross section of the center casing on the line $y-y$, Fig. 5: Fig. 8 is a front elevation, Fig. 9, a side elevation 80 and Fig. 10 a plan of one of the cord holders.

Latitude is allowed herein as to details, since they may be varied or changed at will without departing from the spirit or scope 85 of my invention.

Corresponding and like parts are referred to in the following description and indicated in all the figures of the drawings by the same reference characters. 90

In the drawings, 1 represents a straight-edge, on the upper side of which are mounted a center casing 2 and end casings 3 and 4 of metal and placed preferably adjacent to the lower edge of the straight-edge 1. 95 The center casing 2 consists of a channel plate 5 fastened to the straight-edge 1 by screws 6 and having a longitudinal slot 7 extending its entire length, while the end casings 3 and 4 consist of two plates 8 and 9, 100 each pair of which is held together by intervening tubular studs 10 riveted in the plates 8 and 9, and through the tubular studs 10 screws 11 are passed, which fasten the end casings 3 and 4 to the straight-edge 1, while 105 posts 12 are located between the plates 8 and 9 near their outer end. In the center casing 2 is located a rectangular plate 13, adapted to engage the walls of the center casing 2, in which plate 13 is riveted a 110

stud 14, having a threaded post 15 extending therefrom of smaller diameter than the stud 14 adapted to pass through the slot 7 and on which is mounted a thumb-nut 16. 5 In the casings 2, 3 and 4 are mounted on the studs 10 and in the same plane freely revolving double grooved wheels 17, 18, 19, 20 and 21, around which cords 22 and 23 are adapted to pass, each cord following one 10 and the same relative groove in each wheel as it passes from wheel to wheel, while the posts 12 serve to keep the cords 22 and 23 from becoming detached from the casings 3 and 4. By this arrangement the center casing 2 covers the cords 22 and 23 as they 15 cross from one end to the other of the straight-edge 1, which part of each cord 22 and 23 between the end casings 3 and 4 is the only part in motion, when the 20 straight-edge 1 is being moved.

The straight-edge 1, when mounted upon a drawing board 24, or other flat surface, after it has been placed at any desired angle with reference to a base line on said 25 board or support, is locked at that angle by tightening the thumb-nut 16, so that the channel plate 5 of the center casing 2 will be pressed down upon the top of the stud 14 leaving the wheel 19, which is not so high 30 in elevation as the stud 14, to revolve freely, and thereby the channel plate 5 will be held in a fixed position as will be the straight-edge 1, which may then be moved readily over the drawing-board 24 and the 35 same angle will be constantly maintained while the straight-edge 1 is locked at that angle. Upon loosening the thumb-nut 16 the straight-edge 1 may be easily moved and placed at the angle desired. The 40 wheels 17, 18, 19, 20 and 21 are preferably not in alinement as shown in the drawings in order to allow the cords 22 and 23 to pass freely by each inner wheel 18 and 20 in the end casings 3 and 4 and the wheel 19 in the 45 center casing 2 and thus prevent them from interfering with each other. Moreover, the course of the cords 22 and 23 over the wheels 17, 18, 19, 20 and 21 may be reversed so as to follow the other series of 50 relative grooves in the wheels without affecting the operation of the apparatus, while separate single grooved wheels may be substituted for the double grooved wheels by using three wheels in each end casing and 55 two wheels in the center casing and the same general method of stringing the cords may be used.

When the parts of the attachment have 60 been assembled and fastened to the straight-edge 1 it is mounted on the drawing-board 24 or any flat surface, to the edge of each corner of the top and bottom of which is attached a cord holder 25, 26, 27 and 28, each of which comprises a body portion 29 provided at its lower end with a prong 30, at

its upper end with a downwardly turned portion 31 having notches 32, in which the cords 22 and 23 are fastened, and having an opening 33 therein, through which a screw 34 is inserted to fasten the cord holder to 70 the edge of the drawing-board 24. The downwardly turned portions 31 are placed a sufficient distance above the surface of the drawing-board 24 on its top and bottom edges to permit the straight-edge 1 to be 75 moved underneath the portions 31 clear up to the body portions 29 of the cord holders 25, 26, 27 and 28. Therefore, the straight-edge 1 is allowed to pass freely over practically the entire surface of the drawing-board 24, which is free of obstructions on the sides as well, while full play is allowed across the drawing-board 24 for continuous drawing on paper passed across the drawing-board 24, either vertically or horizontally, since there are no attachments or projections beyond the drawing-board 24 to make it cumbersome or to interfere with the work of the draftsman. 85

In fastening the attachment to a straight-edge or drawing-board one end of the cord 22 is secured to the cord holder 25, from which the cord is passed partly around the wheel 17, thence down to and partly around the wheel 18, across the straight-edge 1 to and 90 around the wheel 20, back to and around the wheel 19, thence up to and partly around the wheel 21 down to the cord holder 26, where the other end of the cord 22 is fastened. The other cord 23 is fastened by 100 one end to the cord holder 27, whence the cord is passed partly around the wheel 21, thence up to and partly around the wheel 20, across the straight-edge 1 to and around the wheel 18, back to and around the wheel 105 19, thence up to and partly around the wheel 17 down to the cord holder 28, where the other end of the cord 23 is fastened. The course of the cords 22 and 23 is shown in Figs. 2, 3 and 4, in which the course of 110 cord 22 is indicated by short arrows and the course of cord 23 by long arrows. By employing this method of arranging the cords 22 and 23 and the coöperating wheels the straight-edge may be moved easily and 115 quickly to any desired angle, while the angle of the straight-edge may be readily changed, either slightly or radically, without adjusting or releasing the ends of the cords 22 and 23 or any of the parts, except 120 the thumb-nut 16. The end of one of the cords 22 or 23 may be provided with a slip noose as in Fig. 1 at cord holder 27, in order to adjust the tension of the cords 22 and 23, so as to retain the straight-edge 1 in a rigid 125 position.

In operation, when it is desired to place and lock the straight-edge 1 at a certain angle or to change its angle the thumb-nut 16 is loosened, when the straight-edge 1 may 130

be easily moved and locked at that particular angle by tightening the thumb-nut 16. Then the straight-edge 1 may be readily moved over the surface of the drawing-board 24 and maintained constantly at the same angle without any further adjustment. In changing the angle of the straight-edge 1 the wheel 19 and coöoperating parts slide through the center casing 2 and the threaded post 15 along the longitudinal slot 7 until the proper angle has been reached by the straight-edge 1, when they remain stationary and the tightening of the thumb-nut 16 locks and maintains the straight-edge 1 at the angle in which it is locked as it is moved over the drawing-board 24. Furthermore, the straight-edge 1 may be readily moved to any position on the drawing-board 24 both before and after the straight-edge 1 has been adjusted to the angle desired.

I claim as new and desire to secure by Letters Patent:—

1. In a drafting apparatus, adapted to be secured on a support having a base line, a straight-edge, wheels attached thereto, cords passing around the said wheels, and means independent of the cords for locking and holding the said straight-edge at a fixed angle to said base line.

2. In a drafting apparatus, adapted to be secured on a support having a base line, a straight-edge, wheels attached thereto, cords passing around the said wheels, and means for simultaneously locking and holding the said straight-edge at a fixed angle to said base line and permitting the said straight-edge to be readily moved and maintained constantly at the same angle.

3. In a drafting apparatus, adapted to be secured on a support having a base line, a straight-edge, wheels attached thereto, cords passing around the said wheels, means independent of the cords for locking and holding the said straight edge at a fixed angle to said base line, and means for altering the relation of one of said wheels with respect to the other of said wheels whereby the angle of the said straight-edge may be readily and quickly changed without any adjustment of the said cords.

4. In a drafting apparatus, adapted to be secured on a support having a base line, a straight-edge, wheels attached thereto, cords passing around the said wheels, means for simultaneously locking and holding the said straight-edge at a fixed angle to said base line and permitting the said straight-edge to be readily moved and maintained constantly at the same angle, and means for altering the relation of one of said wheels with respect to the other of said wheels whereby the angle of the said straight-edge may be readily and quickly changed without any adjustment of the said cords.

5. In a drafting apparatus, adapted to be secured on a support having a base line, a straight-edge, wheels attached thereto, cords passing around the said wheels, means independent of the cords for locking and holding the said straight-edge at a fixed angle to said base line, and means for altering the position of one of said wheels on the straight edge relatively to the other wheels thereon to vary the angle of the straight edge, the said wheels being capable of revolving freely and the cords to move thereover while the said straight-edge is locked at the said angle.

6. In a drafting apparatus, adapted to be secured on a support having a base line, a straight-edge, wheels attached thereto, cords passing around the said wheels, means for simultaneously locking and holding the said straight-edge at a fixed angle to said base line and permitting the said straight-edge to be readily moved and maintained constantly at the same angle, and means for altering the position of one of said wheels on the straight edge with respect to the other wheels thereon whereby the straight edge may be set at different angles, the said wheels being capable of revolving freely and the cords to move thereover while the said straight-edge is locked and maintained at the said angle.

7. In a drafting apparatus, adapted to be secured on a support having a base line, a straight edge, casings attached to the ends of the straight edge and a center casing attached to the portion of the straight edge between said end casings, wheels in the said casings, cords passing around the said wheels, and means coöperating with the said center casing for locking the said straight-edge at the desired angle to said base line.

8. In a drafting apparatus, adapted to be secured on a support having a base line, a straight-edge, casings attached to the ends of the straight edge and a center casing attached to the portion of the straight edge between said end casings, wheels in the said casings, cords passing around the said wheels, means coöperating with the said center casing for locking the said straight-edge at the desired angle, and means for causing the angle of the said straight-edge to said base line to be readily and quickly changed without any adjustment of the said cords.

9. In a drafting apparatus, adapted to be secured on a support having a base line, a straight-edge, casings attached to the ends of the straight edge and a center casing attached to the portion of the straight edge between said end casings, wheels in the said casings, cords passing around the said wheels, and means coöperating with the said center casing for locking the said straight-edge at the desired angle to said straight-

edge, the said wheels being capable of revolving freely and the cords being free to move thereover while the said straight-edge is locked at the said angle.

5 10. In a drafting apparatus, a straight-edge, casings attached to the ends of the straight edge and a center casing attached to the portion of the straight edge between said end casings, wheels in the said casings, cords passing around the said wheels, means for securing said cords adjacent their ends to a support, and means to prevent the said cords from becoming detached from the said end casings.

15 11. In a drafting apparatus, a straight-edge, a center casing attached to the straight-edge intermediately of its ends and provided with a longitudinal slot, end casings attached to each end of the said straight-edge, 20 grooved wheels mounted in the said end casings, a grooved wheel mounted in the said center casing, cords passing around the said wheels and means for securing said cords adjacent their ends to a support.

25 12. In a drafting apparatus, a straight-edge, a center casing attached to the straight-edge intermediately of its ends and provided with a longitudinal slot, end casings attached to each end of the said straight-edge, 30 grooved wheels mounted in the said end casings, a movable rectangular plate in the said center casing, a grooved wheel mounted on a stud in the said plate and shorter in elevation than the said stud, a threaded post 35 extending from the said stud through the slot in the said center casing and of smaller diameter than the said stud, a thumb-nut mounted on the said threaded post, and cords passing around the said wheels and 40 means for securing said cords adjacent their ends to a support.

45 13. In a drafting apparatus, a straight-edge, a center casing attached to the straight-edge intermediately of its ends and provided with a longitudinal slot, end casings attached to each end of the said straight-edge, grooved wheels mounted in the said end casings, a movable rectangular plate in the said center casing, a grooved wheel 50 mounted on a stud in the said plate and shorter in elevation than the said stud, a threaded post extending from the said stud through the slot in the said center casing and of smaller diameter than the said stud, 55 a thumb-nut mounted on the said threaded post, cords passing around the said wheels and having their ends adapted to be secured to a support and posts in the said end casings adjacent to their ends.

60 14. In a drafting apparatus, a drawing-board, a straight-edge thereon, a center casing attached to the straight-edge intermediately of its ends and provided with a longitudinal slot, end casings attached to each 65 end of the said straight-edge, grooved

wheels mounted in the said end casings, a grooved wheel mounted in the said center casing, cords passing around the said wheels, and cord holders attached to the corners of the said drawing-board.

70

15. In a drafting apparatus, a straight-edge, center and end wheels attached to the said straight-edge, and cords passing around the said wheels, one cord adapted to be secured adjacent one end to a drawing board 75 adjacent its upper left-hand corner and passing down to and partly around the outer left-hand wheel, thence down to and partly around the inner left-hand wheel, across the straight-edge to and around the inner 80 right-hand wheel, thence back to and around the center wheel, thence up to and partly around the outer right-hand wheel down toward and having its other end adapted to be secured to the lower right-hand 85 corner, the other cord adapted to be secured adjacent one end to the drawing board adjacent the upper right-hand corner of the board down to and partly around the outer right-hand wheel, thence up to and 90 partly around the inner right-hand wheel, across the straight-edge to and around the inner left-hand wheel, thence back to and around the center wheel, thence up to and partly around the outer left-hand wheel 95 down toward and having its other end adapted to be secured to the lower left-hand corner of the board.

16. In a drafting apparatus, a straight-edge, center and end wheels attached to the 100 said straight-edge, cords passing around the said wheels, one cord adapted to be secured adjacent one end to a drawing board adjacent its upper left-hand corner and passing down to and partly around the outer left-hand wheel, thence down to and partly around the inner left-hand wheel, across the straight-edge to and around the inner right-hand wheel, thence back to and around the center wheel, thence up to and partly 110 around the outer right-hand wheel down toward and having its other end adapted to be secured to the lower right-hand corner, the other cord adapted to be secured adjacent one end to the drawing board adjacent 115 the upper right-hand corner of the board down to and partly around the outer right-hand wheel, thence up to and partly around the inner right-hand wheel, across the straight-edge to and around the inner left-hand wheel, thence back to and around the center wheel, thence up to and partly 120 around the outer left-hand wheel down toward and having its other end adapted to be secured to the lower left-hand corner of 125 the board, and means for locking and holding the said straight-edge at a fixed angle.

17. In a drafting apparatus, a straight-edge, center and end wheels attached to the said straight-edge, cords passing around 130

the said wheels, one cord adapted to be secured adjacent one end to a drawing board adjacent its upper left-hand corner and passing down to and partly around the 5 outer left-hand wheel, thence down to and partly around the inner left-hand wheel, across the straight-edge to and around the inner right-hand wheel, thence back to and around the center wheel, thence up to and 10 partly around the outer right-hand wheel down toward and having its other end adapted to be secured to the lower right-hand corner, the other cord adapted to be secured adjacent one end to the drawing 15 board adjacent the upper right-hand corner of the board down to and partly around the outer right-hand wheel, thence up to and partly around the inner right-hand wheel, across the straight-edge to and around 20 the inner left-hand wheel, thence back to and around the center wheel, thence up to and partly around the outer left-hand wheel down toward and having its other end adapted to be secured to the lower left-hand 25 corner of the board, and means for simultaneously locking and holding the said straight-edge at a fixed angle and permitting the said straight-edge to be readily moved and maintained constantly at the 30 same angle.

18. In a drafting apparatus, a drafting member, crossed cords adapted to be fixed at their ends and having reversely arranged loops formed therein and coöperative with 35 the respective ends of said member, and means for inversely varying the lengths of the respective loops.

19. In a drafting apparatus, a drafting member, a pair of crossed cords adapted 40 to be attached at their ends to a drafting board and having reversely disposed loops formed in their intermediate portions, guiding means on said member coöperative

with the intermediate portions of the cords, and means on said member coöperative 45 with said loops and adjustable to inversely vary the lengths thereof and thus alter the angle of the drafting member relatively to the drafting board.

20. In a drafting apparatus, a straight 50 edge, crossed cords adapted to be fixed at their ends to a drafting board, and having reversely extending loops formed therein, guiding means at the ends of the straight edge coöperative with said cords, and means 55 coöperative with said loops and shiftable longitudinally of the straight edge to inversely vary the lengths of the respective loops and thus vary the angle of the straight edge relatively to the drafting 60 board.

21. In apparatus of the character described, cords arranged in crossed relation and adapted to be attached at their ends to a support, reversely disposed loops being 65 formed in the intermediate portions of said cords, a member having guiding means at its ends coöperative with said cords at opposite sides of the loops therein, and means coöperative with said loops to determine 70 the relative lengths thereof and thereby determine the angular position of said member relatively to the support.

22. In a drafting apparatus, a straight 75 edge, reversely looped cords the ends of which are adapted to be fixed and the intermediate portions of which coöperate with the ends of the straight edge, and means for inversely varying the lengths of the loops in the cords.

In testimony whereof I have affixed my signature in the presence of two witnesses.

ERNEST LORIN FULLER.
